ELECTRICAL NETWORK SYSTEM

Norbert Wiener, Belmont, and Yuk-Wing Lee,
Boston, Mass.

Application September 2, 1931, Serial No. 560,716

29 Claims. (Cl. 178—44)

This invention relates to electrical corrective network systems, and particularly to a new type of electrical network, and to a new method of computing the constants and values of the respective elements of a network system.

In various technical problems, especially in the signalling and communications fields, it is desirable to construct electrical networks having such characteristics that they will pass, or partially or wholly obstruct, any desired electrical vibrations. Difficulty has been experienced in the past in constructing a network having the desired characteristics of control admittance to specified vibration frequencies, and ease and convenience of computation and adjustment.

An object of this invention is to construct an electrical network adapted to preliminary computation of circuit constants for desired network characteristics.

Another object of this invention is to combine a plurality of network elements into a single filter structure having predetermined network characteristics.

Still another object of this invention is to provide a network system having a predetermined admittance curve through a given vibration frequency range, certain of said frequencies being very slightly attenuated and others of said frequencies being partially or entirely attenuated.

Still another object of this invention is to adjust the attenuation of electrical vibrations of a plurality of frequencies in a predetermined ratio according to the frequency.

A further object of this invention is to assemble in a network system a plurality of adjustable members adapted to modify adjustably the transmission and attenuation characteristics of the network.

A still further object is to adjust a plurality of elements in a network system according to computations whereby a desired network characteristic can be obtained.

Still another object is to match the characteristics of a network system to predetermined required characteristics by computation and adjustment of adjustable members according to the values thereof indicated by the computation.

Still another object of this invention is to adjust a single network system to a transmission characteristic curve of any desired shape.

Still another object is to incorporate in a single network system adjustable members adapted to modify the attenuation characteristics thereof to produce any desired degree of attenuation of any vibration frequency over a given range.

In the prior art of electrical network systems, it has been common to construct simple systems adapted to pass a desired vibration frequency band and to attenuate substantially and completely all other frequencies or to pass only vibration frequencies above a given value or below a given value, or to produce a partial attenuation of certain desired frequencies, which systems, however, are not subject to adjustment nor conveniently adapted to preliminary computation of the required electrical values.

This invention provides an electrical network system adapted to produce any desired degree of attenuation of any desired frequency, and any desired ratio between the degrees of attenuation of various frequencies, and is adapted to adjustment of the attenuation characteristics by simple adjustment of simple elements in the network, such as potentiometer resistances. This network system thus is adapted to produce an attenuation curve which is a close approximation within a very small percentage limit of a desired characteristic curve; it being possible by simple adjustment of variable members of the system to obtain any desired curve of attenuation with respect to frequency. The invention further provides a network system, and means for computing the values of components therein, by which the values of the components when adjusted to the computed value produce a network system adapted to reproduce accurately the desired network characteristics.

The network effect is obtained by an adjustment of phase relationships and magnitude of the electrical vibrations, which adjustments may be upon the basis of preliminary computations to produce the desired network characteristics.

Other objects and structural details of this invention will be apparent from the following description when read in connection with the accompanying figures, wherein:

Figure 1 illustrates a method of combining the transfer admittances of symmetrical networks linearly in connection with the general theory of this invention.

Figure 40 is a diagrammatic view illustrating one specific application of the invention to a network including amplifier means.

It is known in the electric circuit theory that the Laplace transform

$$\int_{-\infty}^{\infty} f(x) e^{-ux} dx$$

of a function $f(x)$ vanishing to the left of the origin, is a function analytic over the right half of the complex plane, and satisfying appropriate conditions at infinity. Since the admittance function of a network is a function analytic over the right half of the complex plane, it is possible to expand this function in terms of the Laplace transforms of a complete set of functions defined for positive values of the argument. If the Laplace transforms represent the admittances of a set of known networks, and further, if it is possible to combine the admittances linearly, then the proper combination of these networks will yield a network with any desired admittance function. If we put $u=j\omega$, where

$$j=\sqrt{-1}$$

our Laplace transformation determines and is determined by a Fourier transformation.

We shall write A for

$$a-b\sqrt{-1}$$

when a and b are real, and

$$A=a+b\sqrt{-1}$$

We shall further simplify F(x) into F(x). A class of functions $F_n(\omega)$ with complex values, having the properties

$$\int_{-\infty}^{\infty} F_m(\omega) \bar{F}_n(\omega) d\omega = 0, m \neq n$$

and

$$\int_{-\infty}^{\infty} |F_n(\omega)|^2 d\omega = 1,$$

75

is said to be a normal and orthogonal class of functions over the interval $(-\infty, \infty)$, and further if

$$Y(\omega) = \sum_{n=0}^{\infty} a_n F_n(\omega) \quad (2) \quad 5$$

then

$$a_n = \int_{-\infty}^{\infty} Y(\omega) \bar{F}_n(\omega) d\omega \quad (3) \quad 10$$

If $F_n(\omega)$ are the Fourier transforms of a complete set of functions vanishing to the left of the origin, then $Y(\omega)$ may be taken to represent an admittance function and is expanded in terms of a complete set of normal and orthogonal functions. It is evident that if $F_n(\omega)$ represent the admittances of a set of known networks, any desired physically realizable quadratically summable admittance function $Y(\omega)$ may be obtained 20 by a linear combination of the networks.

The linear combination of transfer admittances of symmetrical networks is possible. Thus in Figure 1, if J, K, L— are four-terminal networks symmetrical with respect to their horizontal axes, 25 as indicated in the figure and are connected to a common generator, then the short circuits connecting the output terminals of every network, having the same voltage both in magnitude and in phase, at all frequencies with reference to the 30 generator, may be connected together without creating any interactions among the networks. The current at the junction S is the algebraic sum of the currents from all of the individual networks and their signs depend upon the polarity of the terminals. Hence we have here a method 35 to combine transfer admittances linearly. In the first instance, this leads to a short-circuit transfer admittance.

In order to introduce loads, generator impedances, and other networks into both ends, use will be made of some circuit equations. These equations may be stated as follows: Let A =driving-point admittance of a four-terminal network across terminals 1 and 2 with terminals 3 and 4 short-circuited as indicated in Fig. 2; let C =driving-point admittance of the network across terminals 3 and 4 with terminals 1 and 2 short-circuited as shown in Figure 3, and let B =transfer admittance of the network with the 50 connections of Figure 4. These admittances are of complex values, and are functions of the frequency. Then, if two networks 1 and 2 are connected in tandem as shown in Figure 5, the three admittances A_0 , B_0 , and C_0 of the combination 55 taken as one single network, that is, the four terminals at the extreme ends of the system are now taken as those of the new network, will be

$$A_0 = A_1 - \frac{B_1^2}{A_2 + C_1}, \quad (4) \quad 60$$

$$B_0 = \frac{B_1 B_2}{A_2 + C_1}, \quad (5)$$

and

$$C_0 = C_1 - \frac{B_2^2}{A_2 + C_1}. \quad (6)$$

The subscripts 1 and 2 indicate the networks to 70 which the quantities belong.

When three networks are connected in tandem, as Figure 6 shows, then the over-all admittances A'_0 , B'_0 , and C'_0 of the triple combination (the four terminals at the extreme ends of the 75

system are taken as those of the new network are

$$A'_0 = A_1 - \frac{B_1^2}{A_2 + C_1} -$$

$$\frac{B_1^2 B_2^2}{[(A_2 + C_1)(A_3 + C_2) - B^2_2](A_4 + C_1)}, \quad (7)$$

$$B'_0 = \frac{B_1 B_2 B_3}{(A_3 + C_2)(A_4 + C_1) - B^2_2}, \quad (8)$$

and

$$C'_0 = C_3 - \frac{B_2^2}{A_3 + C_2} -$$

$$\frac{B_2^2 B_3^2}{[(A_2 + C_1)(A_3 + C_2) - B^2_2](A_4 + C_2)}. \quad (9)$$

$$a_0 = \frac{1}{\pi} \int_0^\pi \left[\text{Real part of } Y\left(\sqrt{\frac{1}{L'C'}} \tan \frac{\theta'}{2}\right) \right] d\theta', \quad (15)$$

$$a_n = \frac{2}{\pi} \int_0^\pi \left[\text{Real part of } Y\left(\sqrt{\frac{1}{L'C'}} \tan \frac{\theta'}{2}\right) \right] \cos n\theta' d\theta' -$$

$$\frac{2}{\pi} \int_0^\pi \left[\text{Imaginary part of } Y\left(\sqrt{\frac{1}{L'C'}} \tan \frac{\theta'}{2}\right) \right] \sin n\theta' d\theta'. \quad (14)$$

To find a complete set of networks by which we synthesize any desired network, we have two possibilities. One possibility is to form a complete set of networks and then orthogonalize the set of functions representing the transfer admittances of the networks. This follows from the fact that a normal and orthogonal complete system of functions can, by the process of orthogonalization, be determined from a complete sequence of linearly independent functions, and such a system is a linear combination of the given functions. Due to the linear character of the combinations, the final design of a network will be composed of a set of networks which are non-orthogonal; that is, the theory of orthogonal functions resulting from linear combinations of the transfer admittances of the component networks may be used in computing the composed networks even though this is physically realized as a physical combination of the unorthogonalized component networks. The other possibility is to find a complete set of networks whose transfer admittances form a set of normal and orthogonal functions.

As an example of the first method, let us consider the set of lattice networks shown in Figure 7. The letter Z represents an impedance. These networks are well known for their phase correcting properties. The transfer admittance B_n at the terminating impedance with n sections between this and the generator is

$$B_n = \frac{1}{2\sqrt{Z_1 Z_2}} \left[\frac{\sqrt{Z_2} - \sqrt{Z_1}}{\sqrt{Z_2} + \sqrt{Z_1}} \right]^n, \quad (10)$$

If Z_1 is a pure inductive reactance, and Z_2 a pure capacitive reactance, that is, $Z_1 = j\omega L'$, and

$$Z_2 = \frac{1}{j\omega C'},$$

where $\omega = 2\pi$ times the frequency f .

$$j = \sqrt{-1},$$

L' = inductance, and C' = capacitance then

$$B'_n = \frac{1}{2} \sqrt{\frac{C'}{L'}} \left[\frac{\sqrt{\frac{1}{L'C'} - j\omega}}{\sqrt{\frac{1}{L'C'} + j\omega}} \right]^n - \frac{1}{2} \sqrt{\frac{C'}{L'}} (\cos n\theta' - j \sin n\theta') \quad (11)$$

Here

$$\theta' = 2 \tan^{-1} \sqrt{L'C' \omega}. \quad (12)$$

We see that the transfer admittances of the complete set of networks with which we started form a normal and orthogonal set of functions, eliminating a further orthogonalization. With an appropriate change of variables, a transfer admittance $Y(\omega)$ may now be represented by a Fourier series giving

$$Y\left(\sqrt{\frac{1}{L'C'}} \tan \frac{\theta'}{2}\right) = \sum_{n=0}^{\infty} a_n (\cos n\theta' - j \sin n\theta') \quad (13)$$

and upon the determination of the coefficients in the usual manner, that is,

15

$$a_0 = \frac{1}{\pi} \int_0^\pi \left[\text{Real part of } Y\left(\sqrt{\frac{1}{L'C'}} \tan \frac{\theta'}{2}\right) \right] d\theta', \quad (15)$$

20

$$a_n = \frac{2}{\pi} \int_0^\pi \left[\text{Real part of } Y\left(\sqrt{\frac{1}{L'C'}} \tan \frac{\theta'}{2}\right) \right] \cos n\theta' d\theta' -$$

25

which may be most easily done graphically, with the aid of a harmonic analyzer, a network may be designed to yield the required characteristic. The structure of such a network is illustrated in Fig. 8. The networks between which the designed network operates are taken into consideration by Equations (7), (8) and (9). Due to the pure-resistance character of the lattice network looking from any junction toward either end, the set of lattice networks may be combined to form a single network such as Fig. 9 illustrates. The second section corresponds to a negative term in a series. The value of the inductances, the capacitances, and the resistances of this network are the results of combination in the usual manner, that is,

$$L_1 = \frac{1}{\sum_{n=1}^n \frac{1}{L'_n}}, \quad L_2 = \frac{1}{\sum_{n=2}^n \frac{1}{L'_n}}, \quad \text{etc.} \quad 40$$

$$C_1 = \sum_{n=1}^n C'_n, \quad C_2 = \sum_{n=2}^n C'_n, \quad \text{etc.} \quad 45$$

$$R = \frac{1}{R'_0 + \sum_{n=1}^n \frac{1}{R'_n}}, \quad \text{and} \quad R_0 = \frac{R'_0}{2}. \quad 50$$

There is another method of combination by which we may add voltages instead of currents leading into an open circuit. This is illustrated in Fig. 10. Each member of the set of networks is terminated into its image impedance through a transformer instead of a direct termination. In this manner, the values of the inductances may be made to vary from section to section, if n is the number of sections, in the order

$$\frac{1}{n}, \frac{1}{n-1}, \frac{1}{n-2}, \dots, 1, \quad 55$$

beginning with the first section, and the capacitances in the order

$$n, n-1, n-2, \dots, 1.$$

The resistance into which the first section terminates is

$$\frac{R}{n+1},$$

R being the image impedance (pure resistance) of the set of networks before combination, and providing for the constant term in the Fourier series. For example, if the network consists of four sections, the inductances may have the values $L_1 = 25 \text{ mh.}$, $L_2 = 33\frac{1}{3} \text{ mh.}$, $L_3 = 50 \text{ mh.}$, and $L_4 = 100 \text{ mh.}$ ($\text{mh.} = \text{millihenrys}$); and the capacitances

75

may have the values $C_1=0.4$ mfd., $C_2=0.3$ mfd., $C_3=0.2$ mfd., and $C_4=0.1$ mfd. (mfd.=microfarads). The resistance adjacent to the first section is

$$5 \quad \frac{1}{n+1} \sqrt{\frac{L}{C}} = \frac{1}{5} \sqrt{\frac{100 \times 10^{-3}}{0.1 \times 10^{-6}}} = 200 \text{ ohms.}$$

As the image impedance of each network before combination is 1,000 ohms of pure resistance, each transformer loaded with a resistance should offer 10 this amount of resistance. The transformers may have the same ratio, and if this ratio is unity, one of the transformers may be eliminated. A Fourier series is represented by proper 15 connections on the resistance terminations of the transformers. Each coefficient is proportional to the amount of resistance across which connections are made, and its sign depends on the polarity of the connections. The voltage across the extreme terminals is the algebraic sum of the 20 component voltages. Since the image impedances of the set of networks is a pure resistance, the voltage across each terminal resistance is directly proportional to the transfer admittance. A network of this sort has a great variety of designable 25 characteristics with only very simple adjustments in the resistance terminations. Fig. 11 gives a voltage ratio characteristic of the network shown in Fig. 12 designed by the above method.

The networks that have been discussed are a 30 non-resonant type. Similar treatments may be extended to the resonant type. A resonant lattice network is shown in Fig. 13. The transfer admittance B''_n of this network at the terminating 35 impedance with n sections between this and the generator is

$$40 \quad B''_n = \frac{1}{2} \sqrt{\frac{C}{L}} \left[\frac{j\omega L + \frac{1}{j\omega C} - \sqrt{\frac{L}{C}}}{j\omega L + \frac{1}{j\omega C} + \sqrt{\frac{L}{C}}} \right]^n \quad (15)$$

$$= \frac{1}{2} \sqrt{\frac{C}{L}} (\cos n\theta'' - j \sin n\theta'')$$

where

$$45 \quad \theta'' = 2 \tan^{-1} \left(\frac{\sqrt{LC}\omega}{1 - LC\omega^2} \right). \quad (16)$$

Similarly to the previous case, a transfer admittance $Y(\omega)$ may be represented by the Fourier series

$$50 \quad Y(\omega) = \sum_{n=0}^{\infty} b_n (\cos n\theta'' - j \sin n\theta'') \quad (17)$$

where ω and θ'' are related by (16).

The methods of connection are identical with

$$55 \quad H_0(\omega) = \sqrt{\frac{1}{2\pi}} \left[\frac{1}{\frac{k}{2} + j\omega} \right],$$

$$60 \quad H_1(\omega) = \sqrt{\frac{1}{2\pi}} \left[-\frac{1}{\frac{k}{2} + j\omega} + \frac{2}{\frac{3k}{2} + j\omega} \right],$$

$$65 \quad H_2(\omega) = \sqrt{\frac{1}{2\pi}} \left[\frac{1}{\frac{k}{2} + j\omega} - \frac{6}{\frac{3k}{2} + j\omega} + \frac{6}{\frac{5k}{2} + j\omega} \right],$$

$$70 \quad H_3(\omega) = \sqrt{\frac{1}{2\pi}} \left[-\frac{1}{\frac{k}{2} + j\omega} + \frac{12}{\frac{3k}{2} + j\omega} - \frac{30}{\frac{5k}{2} + j\omega} + \frac{20}{\frac{7k}{2} + j\omega} \right],$$

$$75 \quad H_4(\omega) = \sqrt{\frac{1}{2\pi}} \left[\frac{1}{\frac{k}{2} + j\omega} - \frac{20}{\frac{3k}{2} + j\omega} + \frac{90}{\frac{5k}{2} + j\omega} - \frac{140}{\frac{7k}{2} + j\omega} + \frac{70}{\frac{9k}{2} + j\omega} \right],$$

$$75 \quad H_5(\omega) = \sqrt{\frac{1}{2\pi}} \left[-\frac{1}{\frac{k}{2} + j\omega} + \frac{30}{\frac{3k}{2} + j\omega} - \frac{210}{\frac{5k}{2} + j\omega} + \frac{560}{\frac{7k}{2} + j\omega} - \frac{630}{\frac{9k}{2} + j\omega} + \frac{252}{\frac{11k}{2} + j\omega} \right],$$

those in the previous case. The only difference in the two cases with regard to the even harmonics is in the angle θ . In the former case, the interval is $(0, \pi)$, and in the latter $(0, 2\pi)$, covering the same frequency range $(0, \infty)$. Figures 14 to 16 illustrate networks of the resonant type. This network may be used when the odd harmonics in the required network characteristic as a function of θ'' are negligible. To supply such odd harmonics as may be needed, a network substantially odd in θ'' may be formed by placing in tandem to a network of the type just discussed a one-stage lattice network so designed as to have an antiresonant point at

$$15 \quad \omega = \frac{1}{\sqrt{LC}}.$$

By combining this network in parallel with a resonant network of the sort just described, we obtain a substantially universally applicable type 20 of resonant network. The difference in the distribution of the frequency in the two angle intervals gives a difference in the two expansions of a given function, thus making one kind of network better suited to some problems than the 25 other.

The second method in finding a set of fundamental networks for the synthesis of networks with specified properties is to find a complete set of networks whose transfer admittances form a 30 set of normal and orthogonal functions. We shall describe an example of this method of synthesis. Consider the functions

$$35 \quad Q_n(e^{-kt}) e^{-\frac{kt}{2}}, \quad (18)$$

where the functions $Q_n(x)$ is $P_n(2x-1)$, and $P_n(w)$ is the n th Legendre polynominal in w . Here k is a positive constant.

Equation 18 is written as indicated above for the following reason:

$$35 \quad f_0' [P_n(2x-1)]^2 dx = f_0' [Q_n(x)]^2 dx = k \int_0^\infty [e^{-\frac{kt}{2}} Q_n(e^{-kt})]^2 dt, \text{ having put } x = e^{-kt}.$$

Let $H_n(\omega)$ be the Fourier transforms of (18). 45 Then, if an admittance function $Y(\omega)$ is

$$45 \quad Y(\omega) = \sum_{n=0}^{\infty} c_n H_n(\omega) \quad (19)$$

the coefficients c_n are

$$50 \quad c_n = (2n+1)k \int_{-\infty}^{\infty} Y(\omega) \overline{H_n(\omega)} d\omega \quad (20)$$

The first nine terms of $H_n(\omega)$ are

55

$$H_0(\omega) = \sqrt{\frac{1}{2\pi}} \left[\frac{1}{\frac{k}{2} + j\omega} \right],$$

60

$$H_1(\omega) = \sqrt{\frac{1}{2\pi}} \left[-\frac{1}{\frac{k}{2} + j\omega} + \frac{2}{\frac{3k}{2} + j\omega} \right],$$

65

$$H_2(\omega) = \sqrt{\frac{1}{2\pi}} \left[\frac{1}{\frac{k}{2} + j\omega} - \frac{6}{\frac{3k}{2} + j\omega} + \frac{6}{\frac{5k}{2} + j\omega} \right],$$

70

$$H_3(\omega) = \sqrt{\frac{1}{2\pi}} \left[-\frac{1}{\frac{k}{2} + j\omega} + \frac{12}{\frac{3k}{2} + j\omega} - \frac{30}{\frac{5k}{2} + j\omega} + \frac{20}{\frac{7k}{2} + j\omega} \right],$$

75

$$H_4(\omega) = \sqrt{\frac{1}{2\pi}} \left[\frac{1}{\frac{k}{2} + j\omega} - \frac{20}{\frac{3k}{2} + j\omega} + \frac{90}{\frac{5k}{2} + j\omega} - \frac{140}{\frac{7k}{2} + j\omega} + \frac{70}{\frac{9k}{2} + j\omega} \right],$$

80

$$H_5(\omega) = \sqrt{\frac{1}{2\pi}} \left[-\frac{1}{\frac{k}{2} + j\omega} + \frac{30}{\frac{3k}{2} + j\omega} - \frac{210}{\frac{5k}{2} + j\omega} + \frac{560}{\frac{7k}{2} + j\omega} - \frac{630}{\frac{9k}{2} + j\omega} + \frac{252}{\frac{11k}{2} + j\omega} \right],$$

85

$$H_6(\omega) = \sqrt{\frac{1}{2\pi}} \left[\frac{1}{k+j\omega} - \frac{42}{3k+j\omega} + \frac{420}{5k+j\omega} - \frac{1680}{7k+j\omega} + \frac{3150}{9k+j\omega} - \frac{2772}{11k+j\omega} + \frac{924}{13k+j\omega} \right],$$

$$5 \quad H_7(\omega) = \sqrt{\frac{1}{2\pi}} \left[\frac{-1}{k+j\omega} + \frac{56}{3k+j\omega} - \frac{756}{5k+j\omega} + \frac{4200}{7k+j\omega} - \frac{11550}{9k+j\omega} + \frac{16632}{11k+j\omega} - \frac{12012}{13k+j\omega} + \frac{3432}{15k+j\omega} \right], \quad 5$$

and

$$10 \quad H_8(\omega) = \sqrt{\frac{1}{2\pi}} \left[\frac{1}{k+j\omega} - \frac{72}{3k+j\omega} + \frac{1260}{5k+j\omega} - \frac{9240}{7k+j\omega} + \frac{34650}{9k+j\omega} - \frac{72072}{11k+j\omega} + \frac{84084}{13k+j\omega} - \frac{51480}{15k+j\omega} + \frac{12870}{17k+j\omega} \right]. \quad 10$$

It may be easily proved that the coefficients c_n are always real.

15 By the use of known mathematical theorems, it has already been shown in a doctoral dissertation by Y. W. Lee presented to the Massachusetts Institute of Technology, Cambridge, Massachusetts, that

$$20 \quad \int_{-\infty}^{\infty} [\text{Real part of } Y(\omega)] [\text{Real part of } H_n(\omega)] d\omega$$

$$25 = \int_{-\infty}^{\infty} [\text{Imaginary part of } Y(\omega)]$$

$$[\text{Imaginary part of } H_n(\omega)] d\omega. \quad (22)$$

30 This relation, and a change of variables

$$(\theta_m = \tan^{-1} \frac{2\omega}{km}, m = 1, 3, 5, \dots)$$

transform the coefficients given by (20) to sums of integrals of the form

$$35 \quad \int_{-\frac{\pi}{2}}^{\frac{\pi}{2}} [\text{Real part of } Y\left(\frac{km}{2} \tan \theta_m\right)] d\theta_m,$$

40 or of the form

$$45 \quad \int_{-\frac{\pi}{2}}^{\frac{\pi}{2}} [\text{Imaginary part of } Y\left(\frac{km}{2} \tan \theta_m\right)] d\theta_m.$$

These integrals may be conveniently evaluated graphically.

The networks corresponding to the functions 50 $H_n(\omega)$ are recognized as inductances in series with resistances. These may be combined in the manner already described to yield short-circuit transfer admittances. Due to the linear character of the combinations, all the first terms of 55 $H_n(\omega)$, and similarly all the other corresponding terms may be combined in computation so that the final network will consist of as many individual circuits, as there are terms in the expansion. A network of this sort is shown in Figure 17. In this figure, and in those where the

present theory is employed, the quantities $a, b, c, d, e, \dots$ are

$$15 \quad a = \sqrt{\frac{1}{2\pi}} (c_0 - c_1 + c_2 - c_3 + c_4 - c_5 + c_6 - c_7 + c_8 - \dots)$$

$$b = \sqrt{\frac{1}{2\pi}} (2c_1 - 6c_2 + 12c_3 - 20c_4 + 30c_5 - 42c_6 + 56c_7 - 72c_8 + \dots) \quad 20$$

$$c = \sqrt{\frac{1}{2\pi}} (6c_2 - 30c_3 + 90c_4 - 210c_5 + 420c_6 - 756c_7 + 1260c_8 - \dots) \quad 25$$

$$d = \sqrt{\frac{1}{2\pi}} (20c_3 - 140c_4 + 560c_5 - 1680c_6 + 4200c_7 - 9240c_8 + \dots) \quad 25$$

$$e = \sqrt{\frac{1}{2\pi}} (70c_4 - 630c_5 + 3150c_6 - 11550c_7 + 34650c_8 - \dots) \quad (23)$$

Loads are added in accordance with the circuit 30 Equations (7) and (9). The characteristics of networks of capacitances and resistances in series differ from those of the inductive circuits by additive constants. These networks have similar applications. A capacitive network is shown 35 in Figure 18.

The two four-terminal networks shown in Figure 20 have, under certain conditions, transfer admittance of the form

$$40 \quad \frac{\alpha}{\beta + j\omega}$$

where α and β are constants. These networks are known to have constant resistance characteristics looking from terminals (1, 2) into the networks. The impedances Z_1 and Z_2 must be such 45 that $Z_1 Z_2 = R^2$. The simplest case is $Z_1 = j\omega L$ and

$$Z_2 = \frac{1}{j\omega C}$$

or vice versa. These networks may be combined 50 in the manner illustrated in Figures 20 to 23. Equations (19) to (23) are applicable to the design of these networks.

A slight modification in this class of networks is found in the orthogonalization of the sequence 55 of functions

$$e^{-kt}, e^{-2kt}, e^{-3kt}, \dots e^{-nkt}.$$

These Fourier transforms $I_n(\omega)$ of the first 60 nine terms of the orthogonalized set of functions are

$$65 \quad I_0(\omega) = \sqrt{\frac{k}{\pi}} \left[\frac{1}{k+j\omega} \right],$$

$$I_1(\omega) = \sqrt{\frac{k}{2\pi}} \left[-\frac{4}{k+j\omega} + \frac{6}{2k+j\omega} \right], \quad 65$$

$$I_2(\omega) = \sqrt{\frac{3k}{\pi}} \left[\frac{3}{k+j\omega} - \frac{12}{2k+j\omega} + \frac{10}{3k+j\omega} \right],$$

$$70 \quad I_3(\omega) = 2\sqrt{\frac{k}{\pi}} \left[-\frac{4}{k+j\omega} + \frac{30}{2k+j\omega} - \frac{60}{3k+j\omega} + \frac{35}{4k+j\omega} \right],$$

$$I_4(\omega) = \frac{1}{2}\sqrt{\frac{5k}{\pi}} \left[\frac{10}{k+j\omega} - \frac{120}{2k+j\omega} + \frac{420}{3k+j\omega} - \frac{560}{4k+j\omega} + \frac{252}{5k+j\omega} \right],$$

$$75 \quad I_5(\omega) = \sqrt{\frac{6k}{\pi}} \left[\frac{6}{k+j\omega} - \frac{105}{2k+j\omega} + \frac{560}{3k+j\omega} - \frac{1260}{4k+j\omega} + \frac{1260}{5k+j\omega} - \frac{462}{6k+j\omega} \right], \quad 75$$

$$I_6(\omega) = \sqrt{\frac{7k}{\pi}} \left[\frac{7}{k+j\omega} - \frac{168}{2k+j\omega} + \frac{1260}{3k+j\omega} - \frac{4200}{4k+j\omega} + \frac{6930}{5k+j\omega} - \frac{5544}{6k+j\omega} + \frac{1716}{7k+j\omega} \right],$$

$$I_7(\omega) = \frac{2}{5} \sqrt{\frac{2k}{\pi}} \left[\frac{40}{k+j\omega} - \frac{1260}{2k+j\omega} + \frac{12600}{3k+j\omega} - \frac{57750}{4k+j\omega} + \frac{138600}{5k+j\omega} - \frac{180180}{6k+j\omega} + \frac{120120}{7k+j\omega} - \frac{32175}{8k+j\omega} \right],$$

and

$$I_8(\omega) = 3 \sqrt{\frac{k}{\pi}} \left[\frac{9}{k+j\omega} - \frac{360}{2k+j\omega} + \frac{4620}{3k+j\omega} - \frac{27720}{4k+j\omega} + \frac{90090}{5k+j\omega} - \frac{168168}{6k+j\omega} + \frac{180180}{7k+j\omega} - \frac{102960}{8k+j\omega} + \frac{24310}{9k+j\omega} \right]. \quad (24)$$

- 10 As is obvious, these functions are subject to the same treatment as that for the functions $H_n(\omega)$. For these functions, we have,

$$15 \quad Y(\omega) = \sum_{n=0}^{\infty} c'_n I_n(\omega) \quad (25)$$

where

$$20 \quad c'_n = \int_{-\infty}^{\infty} Y(\omega) \bar{I}_n(\omega) d\omega \quad (26)$$

Corresponding to the quantities $a, b, c, d, e, \dots$ we have here

$$25 \quad a' = \sqrt{\frac{k}{\pi}} (c'_0 - 2\sqrt{2}c'_1 + 3\sqrt{3}c'_2 - 8c'_3 + 5\sqrt{5}c'_4 + 6\sqrt{6}c'_5 + 7\sqrt{7}c'_6 + 16\sqrt{2}c'_7 + 27c'_8 \pm \dots)$$

$$b' = \sqrt{\frac{k}{\pi}} (3\sqrt{2}c'_1 - 12\sqrt{3}c'_2 + 60c'_3 - 60\sqrt{5}c'_4 - 105\sqrt{6}c'_5 - 168\sqrt{7}c'_6 - 504\sqrt{2}c'_7 - 1080c'_8 \pm \dots)$$

$$30 \quad c' = \sqrt{\frac{k}{\pi}} (10\sqrt{3}c'_2 - 120c'_3 + 210\sqrt{5}c'_4 + 560\sqrt{6}c'_5 + 1260\sqrt{7}c'_6 + 5040\sqrt{2}c'_7 + 13860c'_8 \pm \dots)$$

$$d' = \sqrt{\frac{k}{\pi}} (70c'_3 - 280\sqrt{5}c'_4 - 1260\sqrt{6}c'_5 - 4200\sqrt{7}c'_6 - 23100\sqrt{2}c'_7 - 83160c'_8 \pm \dots)$$

$$35 \quad e' = \sqrt{\frac{k}{\pi}} (126\sqrt{5}c'_4 + 1260\sqrt{6}c'_5 + 6930\sqrt{7}c'_6 + 55440\sqrt{2}c'_7 + 270270c'_8 \pm \dots)$$

etc.

Similar sets of functions are obtainable from the orthogonalization of the sequence of functions

$$40 \quad e^{-\rho_1 t}, e^{-\rho_2 t}, e^{-\rho_3 t}, \dots e^{-\rho_n t}$$

If a four-terminal network of admittances A, B, and C (These quantities have already been defined in an earlier section of this description.)

- 45 is open at one end, say at the end where C is measured as indicated in Figure 24, then the driving-point admittance A'' measured at the other end is

$$50 \quad A'' = A - \frac{B^2}{C} \quad (28)$$

from which we get

$$B = \sqrt{C(A - A'')}$$

- 55 Now, a two-terminal network of preassigned admittance A'' may be designed in terms of the four-terminal networks for a short-circuit transfer admittance B. Opening the proper junction we shall have a two-terminal admittance A''. Assumption has been made that the driving-point admittance A prior to opening the circuit is known. A method of successive approximations may be used here. The use of constant-resistance networks in this design simplifies computations to a great extent since A becomes 60 a constant.

- 65 When $(A - A'')$ vanishes in the right half plane, there exists a branch point making it impossible to realize B by a physical network. It is, however, possible to increase the driving-point conductance of a four-terminal network to any extent without modifying the transfer admittance. This is illustrated in Figure 25. The currents in the four equal resistances flow in such directions that they cancel each other 70 at the short circuit S, which means that the

10 transfer admittance of the network remains unchanged while the driving-point admittance at either end is increased by an amount equal to one of the four equal resistances. All of the 15 four-terminal networks discussed in connection with the synthesis of four-terminal networks may be used for the synthesis of two-terminal networks. Figures 26 to 33 illustrate the two 20 terminal networks under consideration.

Another method in the synthesis of two-terminal networks is in the use of connections 25 shown in Figures 34 and 35. These connections give linear relations between the driving-point

$$25 \quad a' = \sqrt{\frac{k}{\pi}} (c'_0 - 2\sqrt{2}c'_1 + 3\sqrt{3}c'_2 - 8c'_3 + 5\sqrt{5}c'_4 + 6\sqrt{6}c'_5 + 7\sqrt{7}c'_6 + 16\sqrt{2}c'_7 + 27c'_8 \pm \dots)$$

$$30 \quad b' = \sqrt{\frac{k}{\pi}} (3\sqrt{2}c'_1 - 12\sqrt{3}c'_2 + 60c'_3 - 60\sqrt{5}c'_4 - 105\sqrt{6}c'_5 - 168\sqrt{7}c'_6 - 504\sqrt{2}c'_7 - 1080c'_8 \pm \dots)$$

$$35 \quad c' = \sqrt{\frac{k}{\pi}} (10\sqrt{3}c'_2 - 120c'_3 + 210\sqrt{5}c'_4 + 560\sqrt{6}c'_5 + 1260\sqrt{7}c'_6 + 5040\sqrt{2}c'_7 + 13860c'_8 \pm \dots)$$

$$40 \quad d' = \sqrt{\frac{k}{\pi}} (70c'_3 - 280\sqrt{5}c'_4 - 1260\sqrt{6}c'_5 - 4200\sqrt{7}c'_6 - 23100\sqrt{2}c'_7 - 83160c'_8 \pm \dots)$$

$$45 \quad e' = \sqrt{\frac{k}{\pi}} (126\sqrt{5}c'_4 + 1260\sqrt{6}c'_5 + 6930\sqrt{7}c'_6 + 55440\sqrt{2}c'_7 + 270270c'_8 \pm \dots)$$

etc. and transfer admittances of a network under a certain condition.

If a network, symmetrical with respect to both the vertical and the horizontal axes (but not necessarily symmetrical with respect to the diagonals), and whose driving point admittances are A ($A=C$), and whose transfer admittance is B, is connected in the manner shown in Figure 34, then the driving-point admittance M across terminals 5 and 6 is

$$45 \quad M = 2(A+B). \quad (30)$$

If the same network is connected as in Figure 35, then the admittance N across terminals 7 and 8 is

$$50 \quad N = 2(A-B). \quad (31)$$

A complete set of four-terminal networks whose transfer admittances form a set of normal and 55 orthogonal functions, so connected, will result in two sets of two-terminal networks from which two-terminal networks of preassigned characteristics may be synthesized, except that the quantity A needs a further consideration. The net works corresponding to M_n represents the 60 positive terms of a series, and those corresponding to N_n represent the negative terms of the series. A parallel combination of these networks may correctly represent an expansion, but this representation is always accompanied by 65 an extra additive constant which cannot be cancelled except by the introduction of a negative resistance. The difficulty is not a serious one as a two-terminal network is often designed in consideration of other networks in a system, 70 and the constant may be properly disposed of in many cases.

The two sets of two-terminal networks derived from the non-resonant lattice networks are shown in Figure 36. The networks on the left

correspond to the positive terms of a Fourier expansion, and those on the right the negative terms. Figure 37 shows how these networks may be connected. Similar sets of networks are derivable from other sets of four-terminal networks already described.

The admittances of the circuits shown in Figure 38 are, with the constants indicated,

$$10 \quad \frac{1}{\frac{R}{L} + j\omega}$$

for the inductive circuit, and

$$15 \quad \frac{1}{\frac{R}{L} - \frac{1}{R} + j\omega}$$

20 for the capacitive circuit. Functions of the form

$$\frac{\alpha}{\beta + j\omega}$$

25 have been discussed in connection with the synthesis of four-terminal networks, and it is now obvious that a two-terminal network of specified characteristic may also be synthesized by the parallel combination of two sets of simple inductive and capacitive series circuits. Thus a 30 network of the type shown in Figure 39 may be designed in accordance with Equations (19) to (23) or Equations (24) to (27). The inductive circuits represent the positive terms, and the capacitive circuits the negative terms in an expansion.

As a matter of fact, every pair of the two-terminal networks shown in Figure 36 leads to the orthogonalization of the sequence of functions

$$40 \quad \left(\frac{\lambda_1 - j\omega}{\lambda_1 + j\omega}\right)^n, \left(\frac{\lambda_2 - j\omega}{\lambda_2 + j\omega}\right)^n, \left(\frac{\lambda_3 - j\omega}{\lambda_3 + j\omega}\right)^n, \dots, \left(\frac{\lambda_m - j\omega}{\lambda_m + j\omega}\right)^n;$$

45 and may form a basis for synthesis. The simple case of the inductive and capacitive circuits just described is an example of this method of synthesis. All of these two-terminal networks whose admittances bear linear relations with the transfer admittances of the four-terminal networks from which they are derived, have the difficulty 50 of the additive constant.

50 The relations among the admittance parameters have been discussed in a doctoral dissertation by Y. W. Lee, mentioned in an earlier section of this description. Briefly, the conductance and the susceptance of an admittance function are 55 Hilbert transforms of each other, and the same relation exists between the logarithm of the modulus and the phase of the function. Thus, if $P(\omega)$, $Q(\omega)$, $\psi(\omega)$, and $\phi(\omega)$ are the conductance, the susceptance, the modulus, and the phase, respectively, of an admittance $Y(\omega)$, then

$$60 \quad P(\omega) = \frac{1}{\pi} \int_0^\infty \frac{Q(\omega+t) - Q(\omega-t)}{t} dt, \quad (32)$$

$$65 \quad Q(\omega) = -\frac{1}{\pi} \int_0^\infty \frac{P(\omega+t) - P(\omega-t)}{t} dt, \quad (33)$$

$$70 \quad 1n\psi(\omega) = \frac{1}{\pi} \int_0^\infty \frac{\phi(\omega+t) - \phi(\omega-t)}{t} dt, \quad (34)$$

and

$$75 \quad \phi(\omega) = -\frac{1}{\pi} \int_0^\infty \frac{1n\psi(\omega+t) - 1n\psi(\omega-t)}{t} dt, \quad (35)$$

These integrals are defined as principal values.

Equations (32), (33), (34), and (35) expressed in a different form are

$$P(\omega) = -\frac{1}{\pi} \int_0^\infty \cos \omega u du \int_{-\infty}^\infty Q(t) \sin u t dt, \quad (36) \quad 5$$

$$Q(\omega) = -\frac{1}{\pi} \int_0^\infty \sin \omega u du \int_{-\infty}^\infty P(t) \cos u t dt, \quad (37)$$

$$1n\psi(\omega) = -\frac{1}{\pi} \int_0^\infty \cos \omega u du \int_{-\infty}^\infty \phi(t) \sin u t dt, \quad (38) \quad 10$$

and

$$\phi(\omega) = -\frac{1}{\pi} \int_0^\infty \sin \omega u du \int_{-\infty}^\infty 1n\psi(t) \cos u t dt. \quad (39)$$

Since a non-dissipative circuit in parallel with a given circuit affects the susceptance alone, and a pure resistance in parallel with the same circuit amounts merely to the addition of a constant, the reciprocal relations of $P(\omega)$ and $Q(\omega)$ do not always hold. As inductances and capacitances 20 are usually accompanied by resistance, the only exception to these relations in a physical network is, therefore, when a circuit is shunted by a resistance. As is obvious, such a resistance can be easily accounted for in any actual problem. 25

Owing to the fact that a zero of a function is an infinity of its logarithm, the determination of modulus by phase, and vice versa, is not unique. It is, however, possible to avoid this difficulty by further mathematical considerations. 30

A most effective and simple method for obtaining from one given parameter the other three parameters of an admittance is found in the use of the Fourier expansion. It has been shown in an earlier part of this description that an admittance may be represented by a Fourier series with a change of variables. It follows immediately that if the conductance $P(\omega)$ is

$$40 \quad P\left(k \tan \frac{\theta}{2}\right) = \sum_{n=0}^{\infty} a_n \cos n\theta, \quad (40)$$

then the susceptance $Q(\omega)$ is

$$45 \quad Q\left(k \tan \frac{\theta}{2}\right) = -\sum_{n=0}^{\infty} a_n \sin n\theta, \quad (41)$$

or vice versa.

Since the logarithm of the modulus bears to the phase the relation which the conductance bears to the susceptance, the Fourier expansion method 50 is applicable to the determination of modulus by phase, and vice versa; that is, if

$$55 \quad 1n\psi\left(k \tan \frac{\theta}{2}\right) = \sum_{n=0}^{\infty} b_n \cos n\theta, \quad (42)$$

then

$$60 \quad \phi\left(k \tan \frac{\theta}{2}\right) = -\sum_{n=0}^{\infty} b_n \sin n\theta. \quad (43)$$

The reverse is also true.

The embodiment of this invention disclosed in Figure 12, upon construction and test, was found capable of producing an attenuation characteristic curve, such as that shown in Figure 11, and the test curve was found to match the computed 65 curve with a high degree of accuracy, the departure being only a very small percentage error. The characteristic curve of the network is conveniently adjusted and readily modifiable to change the shape of the attenuation characteristic curve in any desired fashion. In the example shown the network has a high transmission at a frequency of 90 cycles with a lesser transmission of frequencies above and below, with a controllable lesser transmission, that is, a controlla- 70 75

ble attenuation, of other frequencies according to the required characteristics. Simple changes of the potentiometers permit the displacement of the peak of the maximum transmission to any desired position in the frequency range. Simultaneously, the degree of attenuation of other frequencies is equally readily controllable independently of the position of the peak of maximum transmission.

10 The device of this invention thus produces a simple electrical network having a small number of adjustable members by means of which any desired network characteristics can be produced, thereby enabling a single corrective network to be used for any purpose; as distinguished from the prior art, in which a given network was adaptable only to a single attenuation characteristic curve, and was adapted to other characteristic curves only after complete rebuilding 15 and reconstruction of the values of all the component parts.

15 The invention does not, however, necessarily reside in the adjustable features as above mentioned, since it is possible by the computation 20 process of this invention to produce a network having non-adjustable elements, which can be computed and constructed in size according to the desired characteristic curve of the network. When so constructed, the system, although non- 25 adjustable without rebuilding, nevertheless produces a simple convenient network system of high efficiency and high accuracy of characteristic curve obtainable from computation.

20 A particular merit of this network system is 30 that, when viewed from the input end, as usually operated, it has the impedance characteristic of a pure resistance, and that when the network is adjustable, the value of this resistance is unaffected by the adjustment. This greatly facilitates 35 the computation of the characteristic which the network must have to produce a desired effect, and minimizes the deleterious effect of reflection of oscillations at the network, which makes the problem of matching characteristics 40 very critical in wave filters of most previous types.

45 By this invention, there is thus produced a new and useful electrical network system, adapted to permit the attenuation to any desired extent of 50 any desired frequencies in a circuit.

55 This invention may be used to feed into a repeater or other amplifying device, as is shown in Figure 40, or may be interpolated between the stages of an amplifier. It may also be used to feed directly or indirectly into a phonograph cutter or other instrument transforming electrical vibrations into a mechanical form. Among its 60 applications, but not exhausting them, are a use in connection with communication circuits, for filtering, balancing, or compensating purposes; a use in connection with television circuits, to which it is peculiarly adapted, owing to the fact that it gives a ready control over phase distortion as well as amplitude distortion; a use in the 65 production of tones or noises of predetermined distribution of energy in frequency; a use in the recording and reproducing of sound; a use as an instrument in the calibration of electrical and acoustical systems, for laboratory, medical, and 70 other purposes; a use in determination of what quality of response in a sound reproducing device is most desirable or pleasing to the human ear. It is possible to embody the principles of this device in mechanical or acoustical form, in accordance with the well-known analogies between 75

electrical vibrating systems and mechanical or acoustical vibrating systems.

8 In several places in the claims it is necessary to refer to quantities which in one particular embodiment of the device may be currents, in other embodiments electromotive forces. In such places the term "electrical vibrations" is used to cover both currents and electromotive forces.

10 While the above description discloses but a limited number of embodiments of the device of this invention, it is possible to produce still other embodiments without departing from the spirit thereof, and it is desired therefore, that only such limitations shall be imposed upon the appended claims as are stated therein or required 15 by the prior art.

15 The invention claimed is:

1. A network having a desired admittance characteristic comprising a plurality of sections, each having an admittance which varies from 20 section to section in accordance with the terms of an orthogonal expansion, so that each section when taken in connection with the preceding section or sections more closely approximates the desired admittance, and connections between 25 said sections.

2. A network comprising a plurality of sections, the elements of which have values differing from section to section and corresponding to the coefficients a_0, a_1, a_2, a_3 , etc. of the expansion 30 of the admittance to be simulated into an orthogonal series of the form

$$a_0 + a_1 F_1(\omega) + a_2 F_2(\omega) + a_3 F_3(\omega) + \dots$$

35 wherein $F_1(\omega), F_2(\omega), F_3(\omega), \dots$ are a set of functions with complex values, satisfying the conditions of orthogonality with respect to the frequency or some function thereof, and ω equals 2 π times the frequency, and connections between 40 said sections.

3. A network comprising a plurality of sections the elements of which have values differing from section to section and corresponding to the coefficients a_0, a_1, a_2, a_3 , etc. of the expansion of the 45 admittance to be simulated into a series of the form

$$\sum_{n=0}^{\infty} a_n (\cos n\theta - j \sin n\theta)$$

50 wherein $\theta = 2 \tan^{-1} k\omega$, k being a positive constant, and ω being 2π times the frequency, and connections between said sections.

4. A network comprising a plurality of sections, the elements of which have values differing from section to section and corresponding to the coefficients a_0, a_1, a_2, a_3 , etc. of the expansion of the admittance to be simulated into a series of 55 the form

$$\sum_{n=0}^{\infty} a_n (\cos n\theta - j \sin n\theta)$$

60 wherein

$$\theta = \tan^{-1} \left(\frac{k_1 \omega}{1 - k_2 \omega^2} \right);$$

65 k_1, k_2 being positive constants; and ω being 2π times the frequency, and connections between 70 said sections.

5. A network comprising a plurality of sections the elements of which have values differing from section to section and corresponding to the coefficients a_0, a_1, a_2, a_3 , etc. of the expansion of the 75

admittance to be simulated into a series of the form

$$\sum_{n=0}^{\infty} a_n U_n(\omega)$$

5 wherein each of the functions $U_n(\omega)$ is a linear combination of functions of the form

$$\frac{1}{k_m + j\omega}$$

10 k_m being positive constants, j being $\sqrt{-1}$, and ω being 2π times the frequency, and connections between said sections.

15 6. A network having a desired admittance characteristic comprising a plurality of sections, each having an admittance which varies from section to section in accordance with the terms of a series which is the result of simplification by grouping of similar terms of an orthogonal series, and connections between said sections.

20 7. A four-terminal corrective network comprising a plurality of current paths having therein different numbers of similar impedance units comprising inductance and capacitative reactance elements, and different resistance elements, said paths lying between common terminals.

25 8. An electrical network system with two terminals, and comprising a plurality of impedances or admittances obtainable by the grouping of terms from a set proceeding, each except for an additive constant, as the terms of a series of orthogonal functions and combined additively in such a way that the total impedance or admittance shall depend in an assigned manner on the frequency, and connections between said impedances or admittances.

30 9. An electrical network system with two terminals, comprising a plurality of impedances or admittances proceeding, each except for an additive constant, as the terms of a series of orthogonal functions and combined additively in such a way that the total impedance or admittance shall depend in an assigned way on the frequency, and connections between said impedances or admittances.

35 10. An electrical network system with two terminals, comprising a plurality of impedances or admittances proceeding, each except for an additive constant, as the terms of a series of orthogonal functions and combined additively, and connections between said impedances or admittances.

40 11. An electrical network system with two terminals, comprising in combination a plurality of impedances or admittances proceeding, except for an additive constant as the terms of a series of orthogonal functions, and connections between said impedances or admittances.

45 12. An electrical network system comprising a series of connected lattice members having inductance elements of varying values arranged in a given numerical sequence and capacitance members of varying values in a similar numerical sequence but in a reverse sense, an electrical path for each of a plurality of the meshes of said lattice members and means for combining the output of said paths into an output circuit.

50 13. An electrical network system comprising a plurality of connected lattice members having inductance elements of varying values, an electrical path for each of a plurality of the meshes of said lattice members, and means for combining the output of said paths into an output circuit.

55 14. An electrical system comprising a plurality of connected lattice members containing imped-

ances of varying values, an electrical path for each of a plurality of the meshes of said lattice members, and means for combining the output of said paths into an output circuit.

60 15. An electrical network system comprising a plurality of connected lattice members having inductance elements of varying values arranged in a given numerical sequence and capacitance members of varying values in a similar numerical sequence but in a reverse sense, the values of said inductance and capacitance progressively varying from one of said lattice members to another, electrical paths leading from said lattice members and means for combining the output of said paths into an output circuit, said paths comprising 10 adjustable impedance members.

65 16. An electrical network system comprising a plurality of connected lattice members having inductance elements of varying values and capacitance members of varying values, electrical paths leading from said lattice members, and means for combining the output of said paths into an output circuit, said paths comprising 20 adjustable impedance members.

70 17. An electrical network system comprising a plurality of connected lattice members containing impedances of varying values, electrical paths leading from said lattice members, and means for combining the output of said paths into an output circuit, said paths comprising 25 adjustable impedance members.

75 18. An electrical network system comprising a plurality of means for producing a plurality of phase shifts without substantial relative amplitude shifts in respective phases of electrical vibrations, an in-put circuit common thereto and connected thereto and means for combining linearly the plurality of vibrations in the shifted phases.

80 19. An electrical network system comprising a plurality of impedance members adapted to modify the phase of electrical vibrations, an in-put circuit common thereto and connected thereto, and a plurality of adjustable members respectively associated with said phase shifting members, comprising adjustable impedances adapted to withdraw therefrom adjusted amounts of phase shifted electrical vibrations.

85 20. An electrical network system comprising a plurality of impedance members adapted to modify the phase of electrical vibration, an in-put circuit common thereto and connected thereto, and a plurality of adjustable members respectively associated with said phase modifying members, comprising adjustable impedance adapted 55 to withdraw therefrom adjusted amounts of phase shifted electrical vibrations without substantial relative amplitude shifts, and means for linearly combining the adjusted amounts of vibration withdrawn into a single circuit.

90 21. An electrical network system comprising a plurality of similar impedance members adapted to modify the phase of electrical vibration, an in-put circuit common thereto and connected thereto, and a plurality of adjustable members 60 respectively associated with said phase modifying members, comprising adjustable impedance means adapted to withdraw therefrom adjusted amounts of phase shifted electrical vibrations 65 without substantial relative amplitude shifts.

95 22. The method of modifying the transmission characteristics of a transmission system whereby said system as a whole will transmit electrical energy of desired amounts at different frequen- 70

cies, which comprises shifting the phase of the electrical energy at various frequencies and selectively impeding the energy of a plurality of said various frequencies of shifted phase a desired amount.

- 5 23. The method of obtaining a desired wave form of electrical vibrations which comprises segregating, from electrical impulses, different harmonic components of shifted phase but of unshifted amplitude, said harmonic components being derived from a harmonic analysis with respect to the impedance as a function of an appropriate function of the time-frequency, and combining the impulses of shifted phase.
- 10 24. The method of modifying the wave form of electrical vibrations over a wide frequency range which comprises segregating various harmonic components therein, said harmonic components being derived from a harmonic analysis with respect to the impedance as a function of an appropriate function of the time-frequency, modifying the value of each of a plurality of said components and in recombining the modified components.
- 15 25. The method of obtaining a set of networks which are non-orthogonal which comprises linearly combining the transfer admittances of component networks.
- 20 26. A set of networks having impedances of values such that the transfer admittances of said

networks form a set of normal and orthogonal networks.

27. The method of modifying the wave form of electrical impulses which comprises shifting the phase of selected portions of the frequency range of said impulses without substantially shifting their amplitude so that the phase of said impulses in various frequency ranges will be substantially the same and in adding said impulses of shifted phase.

10 28. The method of modifying the wave form of electrical impulses which comprises shifting the phase of selected portions of the frequency range of said impulses without substantially shifting their amplitude so that the phase of said impulses in various frequency ranges will be substantially the same and in arithmetically adding selected amounts of said impulses of shifted phase to obtain a desired wave form.

15 29. The method of modifying the wave form of electrical impulses which comprises shifting the phase of selected portions of the frequency range of said impulses without substantially shifting their amplitude so that the phase of said impulses in various frequency ranges will be substantially the same, and in varying the resistance in circuit therewith to vary the frequency of maximum response over a wide range.
